G. F. LINCKS

ELECTRIC CUT-OUT

Filed Dec. 17, 1924

UNITED STATES PATENT OFFICE.

GEORGE FRED LINCKS, OF PITTSFIELD, MASSACHUSETTS, ASSIGNOR TO GENERAL ELECTRIC COMPANY, A CORPORATION OF NEW YORK.

ELECTRIC CUT-OUT.

Application filed December 17, 1924. Serial No. 756,613.

The present invention relates to electric safety devices, and more especially to thermal cut-outs or fuses of high capacity.

In the act of blowing of an electric fuse, 5 a solid conductor explodes or is converted into gas in a very limited time interval and the severity of such explosions and the incident noise and projection of flame is in proportion to the amount of energy flowing 10 at the instant in the circuit protected by the fuse. On account of the serious objections to the behavior of fuses, they have been heretofore restricted in their use to the circuits of relatively low capacities, 15 thereby necessitating the use of the very much more expensive circuit breakers for the protection of the higher capacity circuits.

The object of my invention is the provision of an electric fuse arrangement which shall function satisfactorily to protect high capacity circuits and which shall perform its intended function without possibility of causing injury to persons or things in its 25 vicinity.

One embodiment of the invention is shown in the accompanying drawing in which Fig. 1 is a part longitudinal section and part side elevation of a fusible cut-out; Fig. 2 is a 30 top plan view thereof with certain parts in section; Fig. 3 is a part longitudinal section and part side elevation of the fuse cartridge and one of its receiving contacts; Fig. 4 is a right-hand elevation of the cut-out as indicated in Figs. 1 and 2; Fig. 5 is a cross-section taken on line 5—5 of Fig. 1; Fig. 6 is an end view of fuse cartridge; and Fig. 7 is an enlarged cross-section of the fuse link.

40 The cut-out shown in the drawing is designed to protect an electric circuit carrying normally two hundred amperes current at fifteen thousand volts and to function properly and without injury under a 45 momentary rush of current of upwards of seventy-five thousand kilowatts.

It comprises a closed tank A of heavy boiler plate nearly filled with oil or other arc suppressing fluid, a shell or cartridge 50 fuse B, elevating means C for raising the cartridge above the surface of the oil and returning it into engagement with its stationary contacts D.

The fuse shell or cartridge B comprises a 55 barrel 1 of thick insulating material, such as

horn fibre, with the outer end portions threaded for the reception of heavy end caps 2 and 3. At about one-third of its length from the right-hand end, as shown in Fig. 3, the barrel interior is divided by a 60 partition 4 into an explosion chamber 5 and a spring chamber 6. To secure the partition 4 against displacement, the barrel is counterbored at its right-hand end to provide an internal annular shoulder 7, against 65 which the partition is pressed by an insulating sleeve 8 which bears at its outer end against the end cap 3. A plurality of large holes 9 through the barrel and sleeve 8 about the spring chamber 6 are provided 70 for the free flow of oil into and out of that chamber and a plurality of minute holes 10 through the top and bottom sides of the barrel about the explosion chamber 5 to permit the oil to obtain slow ingress to that 75 chamber, but practically no exit there-through during the time period of blowing of the fusible element 11. The partition 7 has a central aperture 12 normally closed by a plunger 13.

The plunger 13 has a circular head 14 larger than the aperture 12 so that when held against the partition 7 it effects a practical closure of the former. A semi-cylindrical projection 15 from the head extends 80 through the aperture 12, and a similarly shaped clamping plate 16 is secured thereto by set screws 17 for the purpose of 85 electrically and mechanically engaging the end of the fusible element 11 therewith. 90 The plunger head 14 has a peripheral groove 18 in which one end of a contractile helical spring 19 is secured, while the other end of the latter is secured in a similar manner to a circular projection 20 on the inside of a 95 thimble 20' screwed upon the end cap 3. The plunger 13 and the end thimble 20' are also connected by flexible shunts 21 to protect the spring 19 from the heating effects of current therein.

100 The fusible element 11 is a flat strip of soft metal or alloy, with one end straight to be received by the clamping connection 15, 16, while the other end is provided with a flat head 22. It is also provided with the usual reduced cross section at 23 near the clamping connection 15, 16. The left-hand end cap 2 has a keyhole slot 24 in its end wall 25 whereby the flat head 22 of the fusible element 11 may be passed or drawn 110

through from the inside and then secured against return under the tension of the spring 19 by sliding the head sidewise over the contracted portion of the slot 24, as indicated in Fig. 6. Upon screwing the end thimble 26 up against the head 22, good electrical contact therewith will be obtained. The fusible link 11 may be reinforced with a steel wire 27, as indicated in Fig. 7, in case the soft metal of the link used has insufficient tensile strength normally to resist the tension exerted by the spring 19.

The tank A is a rectangular box constructed to withstand severe shocks incident to the explosive action of the fuse, with a lid 28 adapted to be firmly held in place by a plurality of hinged bolts 29 mounted on the sides of the box. Insulator bushings 30 for the circuit wire connectors 31 extend through the opposite end walls of the tank and are secured in place by flanged metal rings 32 cemented to the outside of the bushings and bolts or screws 33 which pass through the flange and engage the end walls of the tank. To make the joint oil-tight, a packing ring 34 is interposed, as indicated in Fig. 3.

The circuit wire connectors 31 comprise metal shells 35 adapted to be independently soldered to the ends of the circuit wires or cables, knurled clamping rings 36 swivelly engaging the shells 35 and screw-threaded upon nuts 37 which are screwed upon the outer ends of conductor bars 38 carried by the bushings 30 and connected at their inner ends to fulcrum blocks 39 for the stationary contacts D. The fulcrum blocks 39 are provided at their outer ends with washers or clamping plates 40 adapted to receive between them the ends of flexible shunt conductors 41 and are held in clamping relation by set screws 42. Packing rings 43 are interposed between the outer washers 40 and the shoulders 43' on the bushings 30 at the bottoms of their end recesses 44. The inner ends of the fulcrum blocks 39 are provided with recesses 45 and cross-bars 46. The stationary contacts D comprise rectangular sheet metal plates 47 with the upper edge 48 curved outwardly and stud brackets 49 riveted centrally to the outer surfaces. The studs of brackets 49 are sufficiently small to enter the recesses 45 of the fulcrum blocks 39 with ample clearance to permit limited universal tilting of the former. The studs are cleft longitudinally to straddle the cross-bars 46 and are themselves provided with cross-bars 50 which serve in conjunction with cross-bars 46 to prevent the longitudinal displacement of the contacts while permitting a certain amount of free axial movement thereof. In order to yieldingly press the contacts D toward each other, helical springs 51 are interposed between the outer surfaces of the plates 47 and the washers

40 and about the fulcrum blocks 39. By attachment of the flexible shunt conductors 41 to the plates 47, the springs 51 are relieved from carrying current and its incident heating effects.

The elevating means C for moving the cartridge fuse B through the oil in the tank and into and out of engagement with the stationary contacts D consists of a rock shaft 52 journaled in the end walls of the tank and provided with three cranks 53, 54 and 55, the first two of which are positioned in the planes of the end caps 2 and 3 of the fuse and carry at their free ends U-shaped leaf springs 56 with apertures in the legs thereof adapted to engage with rounded studs 57 located at diametrical points on the outer plane surfaces of the end caps 2 and 3. The cranks 53 and 54 are of insulating material and held in fixed relation to each other by a bolt 58 passing therethrough parallel to the shaft 52. Both the bolt and shaft are encased in insulation 59 to prevent their becoming conductors for arcing currents. The crank 55 at the outside end of the shaft 52 carries at its free end the operating handle 60 which is transversely movable therein under control of a helical spring 61 which tends to move it toward the end of the tank and its tip 62 into locking relation with shoulders or projections 63 and 64 on the tank A to thereby retain the fuse B in or out of engagement with its contacts D. When the lid 28 of the tank is off, the fuse may be swung up above the top thereof (see Figs. 4 and 5) to permit it to be removed and replaced by another without the operator coming in contact with the bath of oil in the tank.

The tank A is lined with sheet insulation 65, and at its ends about the circuit wire connectors 31 are sheet metal canisters 66 with flanged tubular sections 67 extending through the outer end walls which are adapted to be soldered to the lead sheath of the circuit wires or cables. Packing rings 68 are interposed between the flanges of the tubular sections 66 and the end walls of the canisters and set screws 69 inserted. The top walls of the canisters are pierced to permit insulating material to be poured thereinto after which stopper plugs 70 are inserted. A vent pipe 71 is connected to one end of the tank to permit the latter to relieve itself of gas pressure without scattering of oil.

Electric protective devices must function to protect a circuit from excess flow of current, whether that excess be small as in the case of a gradually applied overload or very great as in the case of a short circuit and any and all conditions between those extremes. The function of the tension spring 19 accordingly is to pull the fuse link 11 in two in case of a gradual softening or weaken-

ing thereof in case of the gradually applied overload. When a short-circuit occurs on the circuit protected, the spring 19 performs no function since the generation of gas pressures in the explosion chamber 5 is so nearly instantaneous that the plunger 13 is displaced in the direction of the spring more rapidly than the spring can act. Upon the disruption of the link 11 under short-circuit flow, a very vigorous arc springs between the severed ends thereof or the terminals to which it was connected. However, as it approaches the aperture 12 in the partition 7, it is cooled and extinguished by the violent 15 rush of oil that takes place through the aperture 12 as the plunger 13 moves backwardly. The explosive action that takes place upon a fuse blowing on short-circuit is so violent and the momentary gas pressures 20 so great that the hard fibre barrel 1 of the fuse cartridge would almost certainly be shattered were it not for the cushioning action of the bath of oil and the stout boiler plate tank. My cut-out has been found in 25 practice to be entirely successful in instantaneously interrupting the flow of electrical energy equivalent to a hundred thousand horse power without injury to itself or other objects and without flame or dangerously 30 hot gases escaping therefrom.

While I have shown and described the best embodiment of the invention known to me, I do not desire to be restricted thereto.

What I claim as new and desire to secure 35 by Letters Patent of the United States, is:—

1. An electric cut-out comprising an insulating shell having a transverse partition provided with a contracted opening and dividing the interior thereof into an explosion proof chamber and a spring chamber, arc suppressing fluid within and surrounding said explosion proof chamber, metal contacts secured to the ends of said shell, a fusible element extending through said explosion proof chamber from one of said contacts, a displaceable terminal connected to the opposite end of said fusible element and disposed adjacent said contracted opening, and spring means disposed in said 45 spring chamber and exerting tension on said displaceable terminal.

2. An electric cut-out comprising an insulating shell, a contact terminal mounted on one end of shell and having a spring 55 connected to the inner side thereof, a second contact terminal fixedly mounted on the other end of said shell and provided with a keyhole slot, and a fusible element connected at one end to said spring and provided at the other end with a head adapted to pass through and be retained against the tension of said spring by the walls of the contracted portion of said keyhole slot.

3. An electric cut-out comprising an insulating shell, fuse terminal contacts mount-

ed upon the ends of said shell, line terminal contacts for electrically engaging said fuse terminal contacts, and means for supporting said line terminal contacts universally tilttable and yieldingly movable toward 70 and from each other.

4. An electric cut-out comprising a cartridge fuse having terminal contacts mounted on the ends thereof, stationary line terminal contacts adapted to engage the ends 75 of said fuse terminal contacts, a fluid container in which said line terminal contacts are mounted, and a rock shaft operable outside said container and having spaced arms fixed thereon adapted to engage opposite 80 ends of said cartridge fuse for depressing and elevating said cartridge fuse through the fluid into and out of engagement with said stationary contacts.

5. An electric cut-out comprising a shell 85 of insulation enclosing a fuse chamber therein and provided with an expulsion aperture through a wall thereof, a fuse terminal disposed in said chamber remote from said expulsion aperture, a second fuse terminal disposed adjacent said aperture and displaceable outwardly therefrom, a fusible element connecting said terminals through said chamber, and arc suppressing fluid normally filling said chamber and adapted to be expelled by the gases of fusion through said 90 expulsion aperture against said displaceable fuse terminal and into intimate contact with any ensuing electric arc.

6. An electric cut-out comprising a shell 100 of insulation enclosing a fuse chamber and provided in opposite side walls with a plurality of minute holes and in an insulating end wall with an expulsion aperture, a fuse terminal fixed to one end of said shell opposite said expulsion aperture, a second fuse terminal normally closing said expulsion aperture and displaceable outwardly therefrom, a fusible element connecting said fuse terminals and extending through said chamber, 105 an arc suppressing fluid surrounding said casing and normally filling said chamber and adapted to be expelled therefrom by the gases of fusion through said expulsion aperture against said displaceable terminal and 110 into intimate contact with any ensuing electric arc.

7. An electric cut-out comprising a tank of arc suppressing fluid, a cylindrical shell of insulation adapted to be immersed in said fluid 115 and having a plurality of minute holes in its walls through which said fluid may enter and completely fill the chamber thereof, a transverse insulating wall fixed therein at one end of said chamber and provided with 120 a contracted expulsion aperture, a fuse terminal fixed to said casing opposite said transverse wall, a second fuse terminal normally closing said expulsion aperture and 125 displaceable outwardly therefrom, a fusible 130

element extending through said chamber from terminal to terminal and serving normally to retain said second terminal in closing position and springs mounted in said shell and connected to said second fuse terminal to effect its displacement upon weakening of the fusible element under overload.

8. An electric cut-out comprising a cylindrical shell of insulation, metallic caps secured to opposite ends thereof, a transverse wall of insulation fixed within said shell to divide the interior thereof into a fuse chamber and a spring chamber and provided with an expulsion aperture, a fuse terminal normally closing said aperture and displaceable into said spring chamber, a fusible element

connected to one of said caps, extending through said fuse chamber and connected to said displaceable fuse terminal to hold it in closing relation to said aperture, springs connected to the other of said caps and to said displaceable fuse terminal, a bath of arc suppressing fluid in which said shell is adapted to be immersed and said shell having provisions to permit restricted flow of said fluid into and to fill said fuse chamber and to permit unrestricted flow of said liquid into and out of said spring chamber.

In witness whereof, I have hereunto set my hand this 11th day of Dec., 1924.

G. FRED LINCKS.
